TRAFFIC SIGNAL

Burnham C. Hammond, Hartford, Mich.

Application May 12, 1938, Serial No. 207,625

1 Claim. (Cl. 116—63)

The present invention relates to new and useful improvements in traffic signals of the green and red go and stop light type for street and highway intersections and has for its primary object to provide, in a manner as hereinafter set forth, a device of this character embodying novel means for indicating the length of time that will elapse before the signals change.

Another very important object of the invention is to provide a traffic signal of the aforementioned character comprising a casing having therein a plurality of partitions of a novel construction and arrangement providing compartments or chambers accommodating the electric lights and the indicator operating mechanism.

Other objects of the invention are to provide a traffic signal of the character described which will be comparatively simple in construction, strong, durable, highly efficient and reliable in use, compact, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is an elevational view of an embodiment of the device.

Figure 2 is a vertical sectional view, taken substantially on the line 2—2 of Fig. 1.

Figure 3 is a view in horizontal section, taken substantially on the line 3—3 of Fig. 1.

Figure 4 is a detail view in elevation of one of the indicators.

Figure 5 is a detail view in section through the light control switch.

Figure 6 is a detail view in plan of the contact plate forming a part of the control switch.

Referring now to the drawings in detail, it will be seen that the embodiment of the invention which has been illustrated comprises a substantially square casing of suitable material which is designated generally by the reference numeral 1. Any suitable supporting means, as at 2, may be provided for the casing 1. The vertical walls of the substantially square casing 1 have mounted therein screens which are designated generally by the reference numeral 3. Each screen 3 comprises green and red segments 4 and 5, respectively.

Mounted vertically in the casing 1 are angular partitions 6 providing light compartments 7. The vertical partitions 6 are angular in horizontal

section, as shown to advantage in Fig. 3 of the drawings, and said partitions including diagonal intermediate portions 8 on which electric lamps 9 are mounted. The portions 8 of the partitions 6 provide a central compartment 10 in the casing 1 extending from the top 11' to the bottom 11" of said casing. It will be observed that each electric lamp 9 is adapted to illuminate a green and a red segment of a pair of the screens 3.

The reference numeral 11 designates a vertical shaft which is journaled in bearings 12 provided therefor in the center compartment 10 of the casing 1. Fixed on the lower portion of the shaft 11 is a bevelled gear 13 which is driven by a shaft 14 from an electric motor 15 in one of the compartments 7. Another bevelled gear 16 is fixed on the vertical shaft 11 at an intermediate point.

The reference numeral 18 designates a plurality of horizontal shafts which are journaled in suitable bearings 19 provided therefor between the spaced partitions 6. This is shown to advantage in Figs. 2 and 3 of the drawings. Bevelled gears 20 are fixed on the inner end portions of the shafts 18 and are driven by the gear 16. Indicators 21, of substantially the shape shown to advantage in Fig. 4 of the drawings, are fixed on the outer end portions of the shafts 18 for rotation closely adjacent the screens 3 in a manner to cast shadows on the screen segments 4 and 5 when the respective lamps 9 are illuminated.

Mounted on one of the shafts 18 is a suitable switch for controlling the electric lamps 9, said switch being designated generally by the reference numeral 22. The switch 22, in the embodiment shown, comprises a ring 23 of suitable insulating material which is fixed on one of the shafts 18. Mounted on the outer periphery of the insulating ring 23 is a conductor plate 24 of substantially the shape shown to advantage in Fig. 6 of the drawings. A brush 25, which is connected with a suitable source of current supply, is engaged with the substantially continuous intermediate portion of the plate 24. A pair of brushes 26 ride on the periphery of the ring 23 for contact with the laterally projecting side portions of the plate 24. One of the brushes 26 is electrically connected to a diagonally opposite pair of the electric lamps 9 while the other brush 26 is electrically connected to the remaining diagonally opposite lamps.

It is thought that the operation of the device will be readily apparent from a consideration of the foregoing. The electric motor 15 is energized from any suitable source of electric current for rotating the shafts 11 and 18 through the various

gears. As the shafts 18 rotate the indicators 21 swing in a circle closely adjacent the inner sides of the screens 3. Through the medium of the switch 22, the diagonally opposite pairs of lamps 9 are alternately energized. Thus, as seen in Fig. 3 of the drawings, the green segments only of the screens facing north and south will be illuminated while the red segments only of the screens facing east and west will be illuminated. As the 10 segments are thus illuminated the indicators 21 travel therebehind for casting a shadow thereon for indicating to both the moving and standing streams of traffic when the signals will change, or rather, to permit an estimate to be made of the 15 length of time that will elapse before a change occurs.

It is believed that the many advantages of a traffic signal constructed in accordance with the present invention will be readily understood and 20 although a preferred embodiment of the device is as illustrated and described, it is to be understood that changes in the details of construction and in the combination and arrangement of parts may be resorted to which will fall within the scope 25 of the invention as claimed.

What is claimed is:

In a traffic signal a casing of rectangular shape in cross section and having an opening in each of its four sides, a sectional light screen covering each opening, the sections being slightly separated at the vertical center of each screen, four partitions vertically arranged in the casing for dividing the same into four chambers, each partition being of substantially angular shape in plan with a diagonal portion connecting one limb of 10 the partition with the other limb and said diagonal portions of the four partitions forming a small vertically arranged central chamber, the limbs of the partitions being separated to form narrow spaces which are vertically arranged, bearing means in said spaces and connected with the partitions, shafts passing through the bearing means, indicators fixed on the outer ends of the shafts and movable over the inner faces of 20 the screens, a drive shaft vertically arranged in the vertical central chamber, gearing connecting said vertical shaft with the first-mentioned shafts.

BURNHAM C. HAMMOND. 25
